UNITED STATES PATENT OFFICE.

FREDERICK JAMES PAYNE AND PERCY CHARLES PAYNE, OF KEYNSHAM, NEAR BRISTOL, ENGLAND.

AIR PUMP OR COMPRESSOR.

Application filed May 14, 1923. Serial No. 638,787.

To all whom it may concern:

Be it known that we, FREDERICK JAMES PAYNE and PERCY CHARLES PAYNE, subjects of the King of Great Britain and Ireland, and residents of Keynsham, near Bristol, in the county of Somerset, England, have invented certain new and useful Improvements in Air Pumps or Compressors, of which the following is a specification.

This invention has reference to double-acting multi-stage pumps or compressors for inflating pneumatic tyres and other purposes, and to pumps or compressors of the type comprising a plurality of single-acting cylinders, the cylinders of each stage being co-axial and fitted with connected pistons which are actuated by a common operating member.

The invention has for its object to provide an improved and simplified construction of pump or compressor of the kind referred to.

In the accompanying drawing Fig. 1 is a longitudinal section of one embodiment of the invention in a two-stage or compound pump especially intended for the inflation of the pneumatic tyres of motor road vehicles, Fig. 2 is a part end view of, and a part transverse section on the line 2—2 in Fig. 1, and Fig. 3 is a section on the line 3—3 in Fig. 1.

Referring to the drawing, 4, 4^a are two half casings having formed in them low pressure cylinders 5, 5^a and high pressure cylinders 6, 6^a respectively, the high pressure cylinders being arranged vertically above and parallel to the low pressure cylinders. The half casings are assembled with their respective low pressure cylinders and high pressure cylinders in axial alignment, and the casings are joined in a plane midway between the co-axial cylinders 6, 6^a and 5, 5^a and secured together by bolts 7 passing through lugs 8. The low pressure cylinders 5, 5^a are fitted with pistons 9, 9^a which are connected to and coupled together by a common rod 10. Similarly, the high pressure cylinders 6, 6^a are fitted with pistons 11, 11^a connected to and coupled together by a rod 12. The pistons 9, 9^a and 11, 11^a are furnished with cup leathers 13.

The pairs of coupled pistons are simultaneously reciprocated in opposite directions by a rocker lever 14 provided with a trunnion 15 which is mounted in a bearing 16 formed on the casing parts 4, 4^a and

through which the trunnion passes to the outside of the casing. The outer end of the trunnion 15 is provided with a socket 17 to receive a hand lever whereby the trunnion and lever 14 can be rocked to reciprocate the pairs of pistons. The ends of the rocker lever 14 are forked and have mounted in them rollers 18, 19 which respectively co-act with a closed slot 20 in the piston rod 10 and an open-ended slot or notch 21 in the piston rod 12.

The cylinders 5, 5^a are provided with inlet ports 22, 22^a which are uncovered and opened by the pistons 9, 9^a at the end of their idle strokes and are swept over by the pistons during their operative strokes. Communication from the low pressure cylinders 5, 5^a to the high pressure cylinders is afforded by the ports 23, 23^a, valve chambers 24, 24^a, wherein are fitted upwardly-opening non-return valves 25, 25^a which seat over the upper ends of the ports 23, 23^a, and ports 26, 26^a. The chambers 24, 24^a also serve to receive valve casings 27, 27^a, the lower ends of which are open to the chambers and wherein are arranged upwardly-opening non-return valves 28, 28^a. Screwed into the upper ends of the casings 27, 27^a are nozzles 29, 29^a, the depending portions of which are open to the casings and also communicate by radial holes 30, 30^a with chambers resulting between the casings and distance pieces or sleeves 31, 31^a clamped between the flanges of the nozzles 29, 29^a and the casings parts 4, 4^a, packing rings 32 ensuring air-tight joints. The distance pieces or sleeves 31, 31^a are connected by an external tube 33 which establishes communication between the chambers formed by the distance pieces or sleeves. A nipple 34 on the nozzle 29 has connected to it a flexible hose 35 for conducting the air under pressure to the tyres and a nipple 34^a on the nozzle 29^a has fitted to it a pressure gauge 36.

The stems of the valves 25, 25^a and 28, 28^a are preferably of triangular cross-section as shown in Fig. 3, or equivalent cross-section, so that while they are maintained centrally in position, spaces result for the passage of the air.

From the above description it will be manifest that air compressed in the low-pressure cylinders 5, 5^a will be discharged into the high pressure cylinders 6, 6^a and

after further compression therein will be discharged through the nipple 34 and hose 35 to the tyre, the air from the cylinder 6^a passing by way of the tube 33 to the nipple 34. It will also be manifest that each pair of complementary low and high pressure cylinders constitutes a single-acting compound pump giving an intermittent delivery, and that the two pairs of complementary low and high pressure cylinders together form a double-acting compound pump yielding a constant delivery and that, accordingly, the higher pressure above the valves 28, 28^a created by the discharges from the high pressure cylinders 6, 6^a will prevent such valves from being opened by the air discharged from the low pressure cylinders to the high pressure cylinders.

Various modifications may be made in the construction described above without departing from the spirit of the invention. For example, instead of the air discharged from the cylinder 6^a being transferred to the delivery nozzle by the external tube 33, such transfer may be effected through a conduit provided in the casing parts 4, 4^a. It is, however, preferred to employ the external tube 33 as it removes the necessity for packing between the two casing parts.

What we claim as our invention and desire to secure by Letters Patent is:—

1. A multi-stage air pump or compressor comprising in combination, two half casings each containing complementary cylinders of each stage, assembled with the cylinders of like stages in axial alignment and joined together in a plane midway between the co-axial cylinders; connected pistons in each two co-axial cylinders, a rocker lever operatively engaged with the connected pistons of each stage, a trunnion on which said rocker lever is mounted and which extends to the outside of the casing parts, and means for operating said trunnion to rock said rocker lever to reciprocate the connected pistons.

2. A multi-stage air pump or compressor comprising in combination, two single-acting multi-stage pumps or compressors as-

sembled with the cylinders of like stages co-axial and joined together in a plane midway between said cylinders, connections between the co-axial pistons of cylinders of like stages, a rocker lever operatively engaged with the connections of the pairs of connected pistons to reciprocate the pairs of pistons of succeeding stages in opposite directions, a trunnion on which said rocker lever is mounted and which extends to the outside of the pump or compressor, means for operating said trunnion to rock said rocker lever to reciprocate the pairs of connected pistons, means for admitting air to the cylinders of the first stage, means for conducting the air from the cylinders of one stage to the complementary cylinders of the next stage, and means for conducting the air from the cylinders of the last stage to a common outlet.

3. A double-acting two-stage air pump or compressor comprising in combination, two casing parts each containing complementary cylinders of the two stages assembled with the cylinders of like stages co-axial and joined together in a plane midway between said co-axial cylinders, pistons in each two co-axial cylinders connected to and coupled together by a common rod, a rocker lever operatively connected with said rods, a trunnion on which said rocker lever is mounted and which is mounted in and extends to the outside of said casing parts, means for actuating the outer end of said trunnion to rock the said rocker lever to reciprocate the pairs of connected pistons in opposite directions, inlet ports to the cylinders of the first stage, ports for conducting the air from the cylinders of the first stage to the cylinders of the second stage, valves for controlling said ports, means for conducting the air from the cylinders of the second stage to a common outlet and valves for controlling such passage of the air.

In witness whereof we have hereunto set our hands.

FREDERICK JAMES PAYNE.
PERCY CHARLES PAYNE.
